MACHINE FOR MOUNTING A COMPONENT CON-
VEYOR AND PROCESSING UNIT FOR USE IN
ELECTRONIC ASSEMBLING

Norman P. Flanders, North Andover, Donald J. T.
Hamm, Ipswich, and Vincent P. Romeo, Danvers,
Mass., assignors to United Shoe Machinery Corpora-
tion, Boston, Mass., a corporation of New Jersey

Filed Mar. 30, 1966, Ser. No. 1,703

Term of patent 14 years

(Cl. D55—1)

Fig. 1

Fig. 2

Fig. 3

Fig. 4

FIG. 1 is a perspective view of a machine for mounting a component conveyor and processing unit for use in electronic assembling, showing our new design; FIG. 2 is an elevational view of the opposite side to that shown in FIG. 1;

FIG. 3 is a front elevational view thereof; and FIG. 4 is a rear elevational view thereof.

The dominant features of our design reside in the portions shown in full lines, the broken lines adjacent the head at the front part of the machine, portions of which are shown broken away, are for illustrative purposes only.

We claim:

The ornamental design for a machine for mounting a component conveyor and processing unit for use in electronic assembling, as shown and described.
